UNITED STATES PATENT OFFICE.

THOMAS J. HEFFERNAN, OF PROVIDENCE, RHODE ISLAND.

COMBUSTION-PROMOTING DEVICE.

Application filed April 12, 1924. Serial No. 706,055.

To all whom it may concern:

Be it known that I, THOMAS J. HEFFERNAN, a citizen of the United States, residing at Providence, in the county of Providence and State of Rhode Island, have invented certain new and useful Improvements in Combustion-Promoting Devices, of which the following is a specification.

This invention relates to an attachment 10 for a coal-burning furnace, for the purpose of promoting combustion therein; and has for its object to mount a chamber in the fire pot of a furnace in which air and gases from the coal are mixed and heated and 15 subsequently discharged into a mass of burning coal.

A further object of this invention is to mount the chamber intermediate the plane of the grate and that of the feed door to 20 contact directly with the burning coal.

The invention further consists of means whereby the chamber may be bolted or secured to the inner side wall of the furnace, in which position it is protected on one side 25 against the heating action of the fiery mass and so prevented from becoming melted.

With these and other objects in view, the invention consists of certain novel features of construction, as will be more fully de- 30 scribed, and particularly pointed out in the appended claims.

In the accompanying drawings:

Figure 1 is a sectional side elevation showing my improved construction of mixing 35 chamber mounted in the fire pot of a furnace.

Figure 2 is a perspective view of the body portion of the chamber with its cap removed and partially broken away to 40 show the perforated inner base or bottom portion thereof.

Figure 3 is a perspective view of the cap member and showing the same notched to 45 fit down over the upper end of the body member.

Figure 4 is a central sectional side elevation of the cap member and showing the thickened wall which is exposed to the burning coal.

It is found in the practical operation of 50 air and gas mixing chambers of this character, that if the same is mounted in the center of the burning mass of coal, the heat generated by passing the entering air and 55 gases through the chamber into the burning mass, is so intense as to melt down the

walls of the chamber. Therefore, in order to reduce the exposed wall area of the chamber to the direct action of the heat, I have mounted the chamber to one side and 60 supported it against the side wall of fire pot, which prevents the heat from completely encircling the chamber and so prevents the same from becoming consumed or melted by the excessive heat generated thereby. 65 I also preferably mount this chamber slightly above the grate surface so as to permit the gas generated at the grate surface to enter and mix with the air in the chamber, which latter is drawn upwardly 70 from below the grate and after they become mixed and heated are discharged into the burning coal at a point intermediate its upper and lower surfaces they are ignited 75 to promote combustion and greatly intensify the heat in the furnace; and the following is a detailed description of one construction of such a mixing chamber whereby these advantageous results may be produced:—

With reference to the drawings, 10 designates the body portion of a gas-mixing chamber which is shown as being in tubular form open at its upper end 11 and provided with a perforated bottom portion 12 through 85 which the air and gases may enter into the body of the chamber. The wall about the lower portion 13 of this chamber is very heavy while that about the upper portion 14 is much thinner, and the upper peripheral edge of the tubular body is provided with a multiplicity of notches 15 whereby the heated gases and air may escape therefrom.

On one side of this body portion, I have 90 formed a flattened base 16 through which openings 17 and 18 are formed which are adapted to receive the heads 19 of the bolts 20 on which this chamber may be supported against the side walls 21 of the furnace 22 with its bottom portion 23 positioned a short distance above the upper surface 24 of the grate 25. A cap 26 is 95 designed to set over the upper end of this body portion and is provided with a skirt 100 27 extending down for a short distance around the thinner wall portion 14 of the body and is arranged to be placed a short distance outwardly from this portion of the body providing a passageway 28 through 105 which the heated combined air and gases pass after flowing out through the notches

15 to be discharged about the lower edge of the skirt into the mass of burning coal.

The inner lip 29 of this cap is considerably thinner than the outer skirt portion so as to fit the space 30 at the upper edge of the body and so determine the width of the passageway 28 for conducting the gases from the chamber into the fiery mass.

10 This lip 29 is notched as at 31 to fit over the upper end of the thickened portion 35 and so cause the cap to set in the correct position. The upper face of this cap is provided with an ear 32 having an 15 eye 33 formed therein to facilitate removal of the cap for cleaning the interior of the mixing chamber when desired.

My device is very simple and practical and also inexpensive in its construction and 20 is very effective in its action, as by its use in drawing air and also a portion of the generated coal gas into the chamber heating it and subsequently discharging the heated mixture into the body of burning 25 coal at a point between its upper and lower surfaces the combustion is materially promoted.

The foregoing description is directed solely towards the construction illustrated, 30 but I desire it to be understood that I reserve the privilege of resorting to all the mechanical changes to which the device is susceptible, the invention being defined and limited only by the terms of the 35 appended claims.

I claim:

1. A mixing chamber for a furnace comprising a body portion open at its top and having inlet ports at its base and outlet ports through the side walls adjacent the top, a cap having a skirt spaced from the side walls of the body portion and means for securing the body portion to the side walls of a fire pot.

45 2. A mixing chamber for a furnace comprising a body portion open at its top and having inlet ports at its bottom and outlet ports through the walls adjacent the top, a cap having a downwardly extending skirt spaced from the side walls of the body por-

tion, elongated openings in the wall of the body portion, bolts passing through the side of the fire pot and the openings in the wall of the body portion for vertically adjusting the mixing chamber within the fire 55 pot.

3. A mixing chamber for a furnace comprising a body portion open at its top and having inlet ports at its base and outlet ports through the walls adjacent the 60 top, the walls of the body portion being inset at their upper portion, a cap having a downwardly extending skirt overlapping and spaced from the inset portion forming a passageway between the skirt and the 65 inset portion of the wall which communicates with the outlet ports through the wall, and means for vertically adjusting the chamber within the fire pot of a furnace.

4. A mixing chamber for a furnace comprising a body portion open at its top, having inlet ports at its base and outlet ports adjacent the top, a cap having a depending skirt spaced from the body portion and means for vertically adjusting the chamber 70 within the fire pot of a furnace. 75

5. A mixing chamber for a furnace comprising a body portion open at its top having inlet ports at its base and outlet ports through and adjacent the top of its walls, 80 the top portion of the walls being thicker than the bottom portions thereof forming a shoulder on the exterior of the wall, a cap having a downwardly extending skirt with its inner side lying in approximately 85

the same vertical plane with the outer side of the thickened portion of the wall, the lower portion of one side of the wall being carried upwardly in the form of a boss to a point adjacent the top of the 90 wall, the said boss and lower portion of the wall having elongated openings therethrough for the reception therein of bolts extending through the wall of the fire pot for vertically adjusting the chamber with 95 relation to the fire pot, the cap being recessed for the reception therein of the boss.

In testimony whereof I affix my signature.

THOMAS J. HEFFERNAN.
